[57] CLAIM

The ornamental design for a car caddy, as shown.

DESCRIPTION

FIG. 1 is a front perspective view of a car caddy embodying my new design;

FIG. 2 is a rear perspective view of the car caddy as shown in FIG. 1;

FIG. 3 is a top plan view thereof on a reduced scale;

FIG. 4 is a front elevational view thereof as seen in the direction of the arrow 4 in FIG. 3;

FIG. 5 is an end elevational view thereof as viewed in the direction of the arrow 5 in FIG. 4;

FIG. 6 is an end elevational view thereof as viewed in the direction of the arrow 6 in FIG. 4; and

FIG. 7 is a rear elevational view thereof as viewed in the direction of the arrow 7 in FIG. 3.
